UNITED STATES PATENT OFFICE

CHARLES L'ENFANT, OF NEW YORK, N. Y.

COIN BANK

Application filed April 16, 1928. Serial No. 270,468.

The present invention relates to improvements in coin banks, and more particularly refers to certain improvements in that type of small coin collection bank adapted to be carried in the pocket and issued by banking institutions as a means of securing the accounts of small depositors.

It is an object of the invention to provide a bank of this type, which will be light in weight, of attractive and neat form, and having no projecting parts but presenting an entirely smooth exterior.

Another object of the invention lies in providing a thin, flat coin bank in which the walls are appropriately reinforced against collapse or expansion and resulting loss of coins; in which the coins may be readily inserted in the bank without fear of their loss through the entrance slot; and in which the extraction of the accumulated coins is made possible readily, although the coins are confined most securely against any casual loss.

A further object of the invention is to afford economy in the construction and issuance of these small banks to enable them to be the subject of more general use.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a perspective view, with parts broken away, showing an improved coin bank constructed in accordance with the present invention.

Figure 2 is a perspective view of the inner partition member.

Figure 3 is a vertical section taken on an enlarged scale along the line 3-3 in Figure 1.

Figure 4 is a horizontal section taken on an enlarged scale along the line 4-4, also in Figure 1.

Figure 5 is a fragmentary detached perspective view showing the lower portion of the bank structure and coin discharge door.

Figure 6 is a side elevation, with parts broken away and parts shown in section, and illustrating a slightly modified form of the invention.

Figure 7 is a vertical sectional view taken through the same.

Figure 8 is a fragmentary perspective view with parts broken away showing a still further modified form of the invention.

Figure 9 is also a fragmentary perspective view showing a further modified form of the invention.

Figure 10 is a longitudinal sectional view taken through the form of invention shown in Figure 9, and

Figure 11 is a perspective view of the gate or door employed in Figures 9 and 10.

Referring more particularly to the drawings, and for the present to that form of the invention illustrated in Figures 1 to 5 inclusive, 15 and 16 designate spaced and opposed walls of an outer casing, made preferably from thin, light material, such as

sheet metal and having longitudinal slots 17 and 18 therein. These slots may be provided in any number, generally corresponding with the number of coin raceways within the casing.

The walls 15 and 16 are preferably formed from the same piece of sheet metal which is bent upon a transverse line, along

which the metal is removed save for the straps 19, between and on opposite sides of

which are provided openings through which the coins are inserted within the raceways in the bank. The walls 15 and 16 are pre-

served in their spaced relation by the abutment of the side or lateral flanges 20 and 21, which are overlapped and secured in any appropriate way as by soldering, welding, etc.

Within the casing is provided a partition member, also preferably constructed of sheet metal or some thin, light, material constructed so as to form with the walls 15 and 16

raceways for the reception of the coins. In the embodiment shown, the partition is composed of two sections 22 and 23 from the

same piece of sheet material folded one upon the other along the transverse line 24, which

is at the lower or coin discharge end of the bank.

The sections 22 and 23 are formed with the lateral flanges 25 and 26 and with the intermediate flanges 27 which are struck from the material of the sections and bent outwardly at substantially right angles toward the opposed walls 15 and 16. The side and intermediate flanges at both sides of the partition member are arranged to engage the opposed walls 15 and 16 of the casing, as shown in Figure 4, whereby not only to space the partition member from both of the opposed walls but also to provide a number of raceways at each side of the partition. It will be noted from Figure 4 that the intermediate flanges 27 are arranged to engage the blank portions of the casing walls between the slots 17 and 18. The coins will thus be exposed through these slots but will be confined against escape.

The upper free edges of the sections 22 and 23 of the partition member are folded over into the flanges 28, as shown in Figures 2 and 3. These flanges are arranged diagonally with respect to the planes of the sections and they are preferably not folded down flat against the sections, but they form partial obstructions at or near the coin entrance slots, reducing the width of the slots below the thickness of the coins, so that the coin must be forced into the slots causing the expansion of the resilient side walls 15 and 16, or the snapping in of the resilient flanges 28. These parts will, of course, return to normal position after the coin is inserted and obstruct the passage of the coin backwardly or outwardly.

Where the walls of the casing are very thin, they are preferably reinforced by studs or rivets 29. These rivets may be headed on the outer surfaces of the walls 15 and 16 and they preferably extend through the slots 30 in the partition sections occasioned by the formation of the intermediate flanges 27. The rivets will prevent the bulging outwardly or the collapse inwardly of the side walls 15 and 16 and the accidental loss of the coins.

One or more rivets or studs 31, as shown in Figure 5, may extend below the partition member and may be received in notches 32 thereof to assist in supporting the partition member and holding it in place within the casing, the flanged end 28 of the partition member being confined by the straps 19 at the other end.

The coins may be removed from the bank through any appropriate door but preferably through a door composed of a resilient or yieldable strip 33 of a width to extend within the lower free open ends of the casing walls 15 and 16. The opposite ends of the strip 33 are offset upwardly and outwardly to provide the tongues 34 for entering the slots 35 in the side flanges 20 and 21. The

door is sprung into place, as indicated in dotted lines in Figure 1.

In the use of the bank, nickels, dimes or coins of other denominations may be received therein according to the size of the coin receiving openings and raceways.

The coins are inserted through the receiving slots adjacent the straps 19 and past the spring flanges 28 into the raceways into which they fall. These raceways are shown to be six in number, three on each side of the partition member, but more or less of the raceways may be provided. When the bank is full of coins, the contents may be removed by prying out the spring door 33. The bank is carried about the person of the depositor and as he is enabled to effect a saving, the coin is placed in the bank. When full the bank is delivered to the banking institution issuing same and there the coins are removed and placed to the credit of the depositor.

As shown in Figures 6 and 7, the construction of outer casing and inner partition member are generally the same except that the flanges 28 at the upper end of the partition member are dispensed with and an inverted substantially U-shaped strip 36 is fitted over the upper ends of the partition sections with the side walls 37 of this channel strip extending down diagonally to partially mask the coin receiving opening and to act as a keeper for preventing the movement of the coins outwardly through the coin receiving slot.

As shown in Figure 6, the lateral flange or portion of the casing at one side is formed with the lug or ledge 38 to receive one end of the resilient door 33^a. This door end is provided with the right angularly extending flange 39 for fitting along the end of the casing.

The opposite end of the spring door 33^a is curled or curved to form a tongue 40 adapted to cooperate with a diagonal or inclined lip 41 formed at the lower end of the casing flange or wall. The door 33^a is bowed, the flanged end 39 inserted and placed on the ledge 38 and the tongue 40 forced inwardly upon the lip 41 against which it will seat when the parts are released.

Referring more particularly to Figure 8, the door 33^b may be U-shaped in cross section and provided at one end with a stud or projection 41 for fitting into a slot 42 in the end wall or flange of the casing. The other end 43 of the door is bent upwardly and outwardly on an inclination to provide a tongue fitting into the slot 44 in the opposite casing wall or flange.

As shown in Figures 9 and 10, the bottom flanges 45 and 46 are shown as provided upon the lower free edges of the casing walls. These flanges are overlapped one upon the other and provide a closed bottom.

The coins are adapted to be removed through a door 47 at one edge of the casing adjoining the bottom. This door 47 is shown more particularly in Figure 11 and is provided with a stud or projection 48 at its lower end adapted to normally fit into openings 49 in the flanges 45 and 46. The upper end of the door is slidably received between the flanges at the side edges of the casing. One of such flanges may be bent inwardly to provide a spring latch 50 for holding the door in the closed position.

The lower end of this spring latch is exposed for prying outwardly whereby to permit the door 47 to be raised, as by the application of a pin through the openings 49 to the stud 48.

The ribs or intermediate flanges 27 of the partition member terminate in such spaced relation to the closed end of the casing as to permit of the passage of the coins from one race to the other through the transverse compartment thus provided, this transverse compartment being in alignment with the door 47. The flanges 25 and 26 of the partition member are, of course, cut away opposite the door 47, as are also the lateral partitions 20 and 21 of the casing. Furthermore, the partition member itself is also preferably notched or cut away, as indicated at 51 in Figure 10.

One of the features of the construction is that there are no end caps or closures having flanges extending over the outer faces of the casing walls. The case presents a smooth external surface suitable for carrying about in the wallet of the depositor without injury to the wallet. Being light in weight and thin, the portability of the device is made practical, while the partition arrangement within reinforces the thin walls of the outer casing and permits the manufacture of the partition itself of very thin stock.

The case being entirely smooth along all sides may be readily inserted and taken out of the leather wallets, and as the case itself is very thin, only the depth of three dimes, two dimes in the passages, and the metal material layers corresponding to the thickness of about another dime, this thinness lends itself also to ready insertion in the wallets without making them bulky.

Furthermore, as the case is made of one sheet of metal bent back on itself and the partition also only of one sheet bent back on itself, the case is assured of this thinness. The case and partition may be readily stamped out, and hence the manufacturing is very inexpensive. Also, as the case and partition is made only of two parts, with the closure of one or more parts, a considerable less number of parts would be required than in similar banks now on the market.

It is obvious that various changes and modifications may be made in the details of con-

struction and design of the above specifically described embodiment of this invention without departing from the spirit thereof, such changes and modifications being restricted only by the scope of the following claims.

What is claimed is:—

1. A coin bank comprising an outer casing having a coin receiving opening, an inner partition member within the casing composed of a thin metallic strip folded upon itself to provide opposed sections, said sections having intermediate flanges struck therefrom and side edge flanges bent therefrom for engaging opposed walls of the casing to provide a plurality of runways at opposite sides of the partition member, the free ends of the folded sectional partition member being bent over diagonally toward the respective inner sides of the casing to form folded flanges arranged to permit the insertion and prevent the escape of the coin through the receiving opening, a closure plate within the end of the casing remote from said receiving opening, said plate having end parts, and the casing having openings detachably receiving the end parts.

2. A coin bank comprising a casing composed of substantially parallel spaced and slotted walls having overlapping lateral flanges secured together, said walls being open at one end and having connecting spaced strips at the other end providing between the same a plurality of coin receiving openings, a partition member within the casing spaced from both of the opposed walls and having providing strips for spacing the partition member from the opposed walls to provide coin receiving raceways in communication with the coin receiving openings, and a removable door at the open ends of the casing walls.

3. A coin bank comprising an outer casing including substantially parallel, oppositely disposed side walls, said casing having a coin receiving opening and provided with an open portion, a partition member within the casing spaced from each of said side walls for providing coin raceways between it and each of said side walls, said partition being laminated, whose free ends face said opening and are bent over diagonally towards the respective walls of the casing, and a removable door for the open portion of the casing constructed and arranged to be fitted to such open portion of the casing by springing the door in place therein.

4. A coin bank comprising an outer casing having a coin receiving opening and a coin discharge opening with slotted portions adjacent the coin discharge opening, a partition member in the casing cooperating therewith to provide coin receiving raceways, and a door of resilient material having end portions adapted to be sprung into the slotted portions of the casing.

5. A coin bank comprising an outer casing

- having a coin receiving opening and a coin discharge opening, a partition member in the casing for providing therewith coin receiving raceways, said casing having at one side of the coin discharge opening a ledge and at its other side an inclined lip, and a resilient door for the discharge opening having a flanged portion receivable on said ledge and having a diagonally disposed tongue adapted to be sprung against and interlocked with said inclined lip.
6. A coin bank, embodying casing sections formed with lateral over-lapping side walls constituting abutments for keeping the sections apart, straps connecting the sections at one end thereof and forming coin deposit slots, a partition disposed between the sections, interval cross connections between the sections extending through the partition and holding the parts permanently together, and a door closure at the end of the sections opposite the strap connections, attachably applied to the sections.
7. A coin bank, embodying casing sections formed with lateral over-lapping side walls affording reinforced abutments for spacing the sections apart, a strap connecting the sections at one end hereof and forming coin deposit slots, a partition disposed between the sections and forming coin chambers therewith, cross members extending from the opposite sides of the partition with their outer edges abutting against the sections, said cross members dividing the chambers into coin raceways corresponding with the deposit slots, and a door closure at the end of the sections opposite the strap connection, attachably applied to the section.
8. A coin bank, embodying casing sections formed with lateral over-lapping side walls affording reinforced abutments for spacing the sections apart, straps connecting the sections at one end thereof and forming coin deposit slots, a partition disposed between the sections and forming coin chambers therewith, said partitions having parts cooperating with the coin slots permitting the insertion of coins into the chambers but preventing the escape of coins therefrom, interval cross abutments between the partition and sections, means connecting the sections for holding them together against the side wall abutments and interval cross abutments, and a door closure at the end of the sections opposite the strap connections attachably applied to the sections.
9. A coin bank, embodying casing sections formed with lateral over-lapping side walls constituting abutments for keeping the sections spaced apart, strap means connecting the sections at one end thereof and forming a coin deposit slot, means for preventing the escape of coins through said slot, studs connecting the sections for maintaining them in assembly against the abutments, and a pry
